Claims priority, application France, June 27, 1963, 939,592

2 Claims. (Cl. 156—458)

ABSTRACT OF THE DISCLOSURE

A labelling machine whose turret has a plurality of cavities adapted to receive bottles and to press labels fed to the periphery of the turret and spanning the cavities into the latter while the suction along one of the edges flanking the cavity is maintained and along the other edge is discontinued to permit the label to be held at one side while the other side slides along the corresponding edge of the cavity to smooth the corresponding end of the label against the bottle; the suction at the other side is then released to free the label which is smoothed against the bottle as the latter passes along its transport path. The machine is a further development of my Patent 3,196,070.

Labelling machines are already known wherein the label extracted from a magazine is gummed and subsequently transferred through suitable means to a turret comprising a plurality of stations, the outer periphery of this turret being formed with cavities adapted to receive the bottles to be labelled. The turret with its peripheral labelling stations is adapted to revolve about a vertical axis past an endless belt conveyor transporting the bottles. The bottles register in succession with the successive peripheral cavities of the turret. The labels are retained on the turret periphery and in front of the aforesaid cavities by suction holes (see my copending application Ser. No. 120,236, filed June 28, 1961, now U.S. Patent No. 3,196,070). Various mechanisms are subsequently operated for applying the label to the bottle. These means may consist for example of pads or blocks lined with cellular rubber projecting from the cavity when the bottle is aligned therewith, each pad or block projecting until it applies the label to the bottle surface. Other devices which may be provided either separately or in combination with the aforesaid means include blower nozzles adapted to blow air for projecting the label from the turret surfaces and directing same onto the desired location of the bottle surface. In machines constructed prior to the present application, e.g. as described in the aforementioned copending application, I have also provided turrets formed with external cavities bounded on the outer peripheral surface of the turret by straight or inclined edges constituting the label-pressing portions as the label is held ahead of and behind the cavity by the aforesaid suction holes. In this case the bottle was sunk into each cavity with the consequence that the gummed label was pushed into the cavity. Unfortunately, various inconveniences were observed in the operation of this arrangement. On the one hand, by causing the bottle to push the label into the cavity, pleats developed in the label in many cases and, on the other hand, front and/or rear marginal portions of the label emerged from the cavity (in the direction of rotation of the turret) and formed vertical strips not adhering to the bottle since the further penetration of the bottle into the cavity ceased when the bottle contacted the edges or side portions of this cavity.

Under these conditions, it was necessary to complete

2

the application of the leading and trailing edges of the label by using either blowing devices as mentioned hereinabove or smoothing devices. Yet, when a bottle leaves the labelling station with a label having marginal portions not adhering to the bottle surface, these marginal portions are likely to be folded or crumpled so that they cannot easily be brought into contact with the bottle as required.

It is the principal object of the present invention to provide an improved labelling device which makes it possible to dispense with the use of fragile or complicated complementary mechanisms or with the use of blowers for acting upon the leading and trailing marginal portions of the label at the labelling station. This device, constituting a considerable improvement over hitherto known devices and arrangements, is nevertheless extremely simple and particularly reliable the system thus provides for properly fitting or tensioning the label at the labelling station at either end of the label by pressing the label against the bottle when the latter is introduced into the turret cavity, thereby avoiding folds, pleats and the like while causing the label to adhere completely to the bottle surface. Furthermore, with this device the provision of a marginal label portion gummed but not adhering to the bottle can be dispensed with, at least at one end of the label. Thus, by simply selecting the label end on which it is desired to leave a strip not adhering to the bottle and with due regard for the smoothing means provided at the exit end of the labelling station, this projecting marginal portion may be caused to adhere to the bottle surface safely and without any risk of crumpling, tearing or folding thereof.

This improved device comprises, at the front and rear ends of each peripheral cavity formed in the turret, a plurality of suction holes disposed in the vicinity of the turret's peripheral surface, the suction effect produced through these holes being so adjustable, that when the bottle is being inserted into the cavity, until it engages the edges bounding same, the suction is discontinued on one side. Thus, as a consequence of the thrust applied through the bottle, one of the marginal portions of the label slips over the outer surface of the turret and the label is wrapped around the bottle under a certain tension, the label slippage being so calculated that when the bottle engages the edges bounding the ingress of the cavity the sliding marginal portion of the label is applied along the corresponding line of contact between the bottle and the corresponding edge.

According to a specific embodiment of this invention, the suction effected through the front suction holes is released first and permits the sliding movement of the label over the turret surface, the rear suction holes being kept operating to prevent any slippage of the label on this side.

According to another feature of this invention, the means provided for smoothing the label at the exit end of the labelling station to complete the adherence of the trailing edge of the label to the bottle is such that the bottle is rotated in a sense opposite to the turret rotation.

Other features and advantages of this invention will appear as the following descriptions proceeds with reference to the attached drawing in which:

FIG. 1 is a diagrammatic elevational view representing the development of the peripheral plane of a labelling turret, wherein the upper portion illustrates a cavity adapted to receive the neck of a bottle for applying a small label thereon, the lower portion showing another cavity for receiving the bottle body for applying the main label thereon;

FIG. 2 is a diagrammatic and fragmentary sectional view showing the top of a labelling station with a bottle

registering with the corresponding cavity formed on the outer periphery of the turret;

FIGS. 3 and 4 are views similar to FIG. 2, showing the sequence of steps corresponding to the introduction of the bottle into the cavity; and

FIG. 5 shows the bottle extracted from the labelling station and being conveyed towards the smoothing station for causing the nonadhering trailing edge of the label to bond to the bottle surface.

In the embodiment illustrated in FIG. 1 the reference characters 1a and 1b designate the upper and lower turret elements in which cavities such as 2 and 3 are formed.

The outer periphery of the turret may comprise, for example, ten or more labelling stations as shown in my above-mentioned copending application. Each labelling station consists of a cavity 2 used for applying the small label 4 and of a larger cavity 3 adapted to apply the main label 5. The dot-dash lines 6 designate the bottle to which the small and main labels 4, 5 are to be applied. The cavities 2 and 3 have a certain depth and constitute therefore recesses in the outer periphery of the turret which are bounded on the cylindrical surface of this turret by edges 2a, 2b on the one hand and edges 3a, 3b on the other. The inner and outer contours of these cavities or recesses depend essentially on the shape of the bottles to be labelled, not on the label dimensions. On the outer peripheral surface of the turret framing these cavities and along these edges, suction holes or cups are provided at the front 2c or 3c and at the rear 2d or 3d. These suction holes or cups are termed "front" ("forwardly") or "rear" ("rearwardly") with respect to the direction of rotation of the turret which is assumed to revolve in the direction shown by the arrows 7 and 8. These suction holes are intended for keeping the small and main labels tensioned over the turret surface across the apertures constituted by the cavities 2 and 3.

In FIGS. 2, 3 and 4 of the drawing, the same reference characters as in FIG. 1 are used to designate the component elements of turret 1b in connection with the application of the main label. However, the following description is also applicable in all respects to the pasting of the small label onto the bottle neck.

When a bottle registers radially with the cavity 3, the label 5 transferred from the gumming station to the turret is preferably tensioned between the edges 3a and 3b at the front and rear ends respectively of cavity 3. The trailing edge 5a of label 5 is held by the suction produced through holes 3d, and the leading edge 5b of this label is retained by the suction produced through holes 3c. This is indicated by the arrows 11, 12 in FIG. 2. Then, by actuating a mechanism such as that of my prior patent the bottle 6 is moved towards the cavity as shown in FIG. 3, the bottle continuing its movement towards the center of the turret until it attains the limiting inner position shown in FIG. 4. From the moment the bottle 6 contacts the label (FIG. 3) the distribution of suction to the front and rear holes is altered so that the suction produced at the holes 3c becomes a definitely weaker than that produced at the holes 3d (arrow 11, FIGS. 3 and 4). This unbalance or uneven distribution of vacuum is such that the pressure exerted by the bottle on the label causes the label edge 5b to slip over the outer peripheral surface of the turret as the label is gradually caused to assume a part-cylindrical configuration until it conforms to the curvature of the bottle body. During this progressive penetration of cavity 3 by bottle 6, the label remains nevertheless tensioned, thus curving around the bottle body as the latter approaches its point of deepest penetration (FIG. 4) of cavity 3. It is clear that during this radially inward movement the label tension avoids the formation of pleats of folds while causing the label to adhere strongly to the bottle body.

It is possible, by carefully calculating the width of the above-defined marginal portion or strip 5b, to stop the slippage of this strip just when the bottle engages

simultaneously both edges 3a and 3b, the leading edge 5c (FIG. 4) of the label registering more particularly, if desired, with the line of contact between the edge 3b and the bottle 6. Thus, with this arrangement the leading or front portion of the label will become perfectly adherent to the bottle, up to its extreme limit. Nevertheless, although the rear portion 5a of the label is gummed, it is retained on the turret by the suction effect produced through the rear holes 3d during this stage of the labelling operation. When the bottle 6 has completed its engagement with the edges 3a and 3b, a suitable mechanical contact may be used for discontinuing the suction through the holes 3d and thus release the strip or marginal portion 5a (FIG. 5). Then the bottle moves out from the cavity 3 and is transferred to the smoothing station with counterclockwise rotation, as indicated by arrow 9, opposite to the clockwise rotation of the turret as symbolized by the arrows 7 and 8, so that the rear or trailing edge 5a of the label may be caused to adhere perfectly, without any risk of folding or pleating, to the corresponding portion of the bottle body. It may be noted that the bottle approaches the smoothing station with the label portion 5c adhering perfectly to the bottle body, thereby preventing the formation of any fold or pleat.

Reference to my prior Patent No. 3,196,070 shows that the relative radial motion of turret 1a or 1b and bottle 6 in the instant application can be simply brought about by rotation of the turret about its axis (clockwise, arrow 7) while the bottle travels along a linear guideway tangential to the periphery of the turret. Suction in channel 3c adjacent the leading edge of cavity 3 is cut off or sharply reduced in a position of incipient penetration (FIG. 3), the suction in channel 3d at the trailing edge being maintained until after the bottle 6 reaches the point of deepest penetration (FIG. 4) which is positively determined by the inwardly converging flanks of the cavity which has a trapezoidal cross-section in the plane of rotation.

Mention is made in the foregoing of the unbalance produced between the suction effects through holes 3c and 3d respectively, and in this connection it may be noted that this unbalance, given equal negative pressures may be obtained in a simple manner by suitably proportioning the surface area of the suction holes, the holes 3d being larger than holes 3c.

The technique whereby the label is caused to slip forwardly is obviously also applicable in the case of a backward-slipping label. In this case it is the rear portion of the label that is bonded up to its endmost transverse marginal portion while the non-adhering marginal portion is located at the front. This would further require that when the bottle is transferred from the labelling station to the smoothing station it is rotated in the opposite direction with respect to the direction that shown by the arrow 9.

It will be noted however that it is preferably to retain the label by its trailing edge and to allow it to slip forwardly, for in this preferred case a rotation of about only one fourth of a revolution in the direction of the arrow 9 is sufficient at the smoothing station, instead of about three-quarters of a revolution if the rotation is effected in the opposite direction.

Of course, many modifications and variations may be made of the embodiment shown and described herein, without departing from the spirit and scope of the invention as set forth in the appended claims.

Thus, notably, the above-described slipping movement of the label may also be used in the case of containers having special contours, requiring the curving of the label about an axis other than a transverse axis.

What I claim is:

1. In a labelling machine having a turret rotatable about an axis and provided with at least one peripheral cavity flanked by first suction means at a leading edge and second suction means at a trailing edge of said cavity

as seen in the direction of rotation, said suction means being adapted to hold a label with an outwardly directed adhesive surface stretched across said cavity upon approaching the location of a generally cylindrical container adapted to have said label affixed thereto on penetrating partly into said cavity, the improvement wherein said first and second suction means are provided with control means for making one of said suction means substantially less effective than the other suction means upon incipient penetration of said container into said cavity, whereby one end of the label is released and applied by the adjoining cavity edge against the surface of the container while the other end of the label remains fixed to the turret, and for subsequently deactivating said other suction means to release the label completely. 15

2. The improvement defined in claim 1 wherein the

spacing of said edges is so related to the length of said label that said one end comes into full contact with the container surface at the point of deepest penetration, said cavity having inwardly converging front and rear flanks for positively defining said point of deepest penetration.
